UNITED STATES PATENT OFFICE.

JAMES E. PLEW, OF CHICAGO, ILLINOIS.

STEP-BY-STEP-MOVEMENT CONTROLLER.

Application filed December 20, 1920. Serial No. 431,884.

To all whom it may concern:

Be it known that I, JAMES E. PLEW, a citizen of the United States, residing at Chicago, county of Cook, State of Illinois, have invented a certain new and useful Improvement in Step-by-Step-Movement Controllers, and declare the following to be a full, clear, and exact description of the same, such as will enable others skilled in the art 10 to which it pertains to make and use the same, reference being had to the accompanying drawings, which form a part of this specification.

My invention has for its object, specifically 15 considered, to produce a simple and novel attachment for a calculating machine or the like which will insure a step by step movement of the carriage such that the carriage will not accidentally be moved through a 20 greater number of steps than desired.

In such devices of this kind with which I am familiar the blow or shock of stopping the carriage comes upon the actuating lever and the toothed rack with which the lever 25 co-operates to hold the carriage in any desired position. A further object of the present invention is to produce a step by step mechanism that will relieve the parts which definitely hold or lock the carriage in 30 its various positions from the shock of stopping the carriage and permit them to move relatively to each other at the instant of stopping, freely and without a wearing action between them.

In carrying out my invention I find that it may be embodied in a simple mechanism which may be fastened to existing machines and therefore, my invention, in its broader aspects, may be said to have for its object 40 to produce a simple and novel mechanism by means of which the movement of a traveling member may be confined to a step by step movement.

The various features of novelty whereby 45 my invention is characterized will herein-after be pointed out with particularity in the claims; but, for a full understanding of my invention and of its objects and advantages, reference may be had to the following detailed description taken in connection with the accompanying drawing, wherein:

Figure 1 is a front elevation of so much of a calculating machine as is necessary to illustrate the application of my invention

thereto, the device being shown in a position of rest;

Fig. 2 is a view similar to Fig. 1, showing the relation of the parts when the carriage has been moved toward the right a distance somewhat less than a full step;

Fig. 3 is a view similar to Figs. 1 and 2, showing the relations of the parts upon the completion of a step, just prior to the release of the auxiliary actuating lever used to move the carriage through that step;

Fig. 4 is a section taken approximately on line 4—4 of Fig. 1;

Fig. 5 is a section taken approximately on line 5—5 of Fig. 2; and

Fig. 6 is a top plan view of the supporting base for the carriage showing the relation between the usual toothed rack and the toothed member or rack forming part of the attachment.

Referring to the drawing, 1 represents the base of a calculating machine, on which base is mounted a sliding carriage, 2, movable in opposite directions. The base of the machine rests on a suitable slab or support, 3. The carriage has mounted thereon and movable therewith a suitable shifting device which, in the arrangement shown, consists of a spring-pressed locking lever, 4, projecting from the front thereof and swinging in a plane at right angles to the direction of movement of the carriage, together with a rack formed by cutting notches, 5, in the top face of the base in position to be engaged by the inner end of the lever. These parts are old and well known, as will appear by reference to the patent to Jahnz, No. 946,367, dated January 11, 1910, for example, and are used by me only for the purposes of illustration.

In lieu of the stationary finger pieces usually fixed to the carriage on opposite sides of the controlling lever, I employ movable finger pieces, 6, 6, each carried on one arm of a bell crank lever, 7, mounted to oscillate on a supporting pin or stud, 8. A spring, 9, between each of the pins or studs, 8, and the corresponding bell crank lever tends constantly to hold the lever in such position that the finger piece thereon will be vertical as shown in Fig. 1 and, so far as the right hand finger piece is concerned, also in Figs. 2 and 3. There is fixed to the controlling lever, 4, a depending post, 10,

having an enlarged head, 11, producing upwardly-directed shoulders on opposite sides of the post at the lower end. One arm of each of the bell crank levers normally stands approximately horizontal and, on the free end thereof, is hung a pawl, 12, having a tooth, 13, adapted to interlock with the adjacent side of the head 11; there being a spring, 14, between each pawl and its supporting lever, which spring tends constantly to press the free end of the pawl toward the member 10.

On the front of the base of the machine is fixed a bar, 15, having teeth, 16, distributed along its upper edge. The spacing between the teeth 16 is equal to the spacing between the notches, 5, with which the controlling lever, 4, co-operates. The free end of each of the pawls, 13, is in the form of a downwardly-projecting nose, 17, adapted to enter between the teeth on the stationary rack bar, 15, when the corresponding finger piece is pressed laterally.

The parts are so proportioned that when one of the finger pieces is pressed laterally, the pawl carried thereby pulls down on the head 11 attached to the controlling lever of the carriage, so as to lift the inner end of the lever out of the particular notch, 5, with which it happens to be engaged. Thereupon, if the lateral thrust on the finger piece is great enough, the carriage starts to travel. The nose of the pawl which has been depressed enters between two of the teeth on the bar, 15, before the main controlling lever is entirely free from the notch out of which it is lifted. Consequently as the carriage travels laterally, one of the teeth, 16, will engage the nose of the oncoming pawl, bringing the free end of the pawl to rest and permitting the pivoted end to travel ahead. The result is that the pawl which for the time being happens to be the actuating pawl, is disconnected from the head on the main controlling lever as illustrated in Fig. 2. There is now nothing to prevent the controlling lever from assuming a locking position whenever the carriage has traveled far enough to bring the inner end of the locking lever into registration with the notch next to the one out of which the locking lever has just been lifted. However, in the positions of the parts as shown in Fig. 2, the inner end of the locking or controlling lever is still resting on a high portion of the base between two of the notches 5. As the movement of the carriage continues, the arm of the bell crank lever which is carrying the actuating pawl engages with a pin or stop 18, on the carriage and thus limits the swinging movement of the bell crank lever, the shoulder or tooth, 13, on the actuating pawl comes in contact with the upper edge of one of the teeth 16, and the nose of the actuating pawl engages

with the adjacent side of the next tooth, 16, behind it; the final condition being that illustrated in Fig. 3 where the movement of the carriage has been arrested by reason of the fact that the actuating pawl has become a lever fulcrumed at its middle upon one of the teeth 16 and engaged at its lower end by one of the other teeth, whereby a continued movement of the upper ends of the pawl, in the direction in which it has been going, is impossible. This final condition is reached just as the main controlling or locking lever registers with the slot into which its inner end is to drop. Therefore, as the carriage comes to rest, the front end of the main locking or controlling lever flies up and the rear end seats itself in the proper notch without being pressed against either of the side bounding walls of the notch, and therefore without being forced to slide over either of such walls while in frictional contact therewith; the main controlling or locking lever being freely movable up and down. As soon as the finger piece by means of which the carriage has been pushed along is released, the parts all assume the positions illustrated in Fig. 1 except, of course, that the carriage has moved ahead one step.

The same cycle of operations is carried out when the carriage is shifted in one direction as when it is shifted in the other direction, it being only a question which of the finger pieces is actuated.

It will thus be seen that I have produced a simple and novel attachment which is all on the exterior of the machine, so that it may be applied to an existing machine without altering the latter. Furthermore, I am able to obtain the step by step movement with the use of finger pieces placed in the same positions as heretofore, the only difference being that they are movably supported instead of being stationary. It will also be seen that by placing on the attachment the whole work of bringing the carriage to rest, wear in the carriage-locking mechanism will be reduced to a minimum because of the entire freedom of the locking lever to move up and down without frictionally engaging the stationary part, at the time the carriage is brought to rest after having moved a step in one direction or the other.

It will further be seen that if it is desired to move the carriage in one direction or the other without making it go step by step, this can be accomplished by simply pressing down on the outer end of the controlling or locking lever, without taking hold of either finger piece, but using the controlling or locking lever as a finger piece for moving the carriage.

While I have illustrated and described with particularity only a single preferred form of my invention, I do not desire to be limited to the exact structural details thus

illustrated and described; but intend to cover all forms and arrangements which come within the terms employed in the definitions of my invention constituting the appended 5 claims.

I claim:

1. The combination with a movable carriage, of a vertically-swinging locking lever mounted on said carriage, a horizontal stationary toothed bar arranged below said lever, finger pieces movably supported on the carriage on opposite sides of said lever, a part depending from said lever and having at its lower end upwardly directed shoulders 10 on opposite sides thereof, pawls associated with said finger pieces and normally engaging with said shoulders, each of said pawls having a part adapted to enter between two of the teeth on said bar when the corresponding finger piece is actuated in a direction to move the carriage.
2. The combination with a movable carriage, of a locking or controlling lever mounted on the carriage and movable in a vertical plane, two bell crank levers mounted 25 on the carriage on opposite sides of the locking lever and each having an arm extending vertically and another arm extending toward the locking lever, a finger piece on the vertical arm of each bell crank lever, a pawl hung on the free end of the horizontal arm of each bell crank lever, a part depending from the locking lever between said pawls and having at its lower end upwardly-directed shoulders on opposite sides thereof engaged by the pawls, a stationary toothed bar lying below said pawls and in the same vertical plane, said pawls having noses at 30 their lower ends adapted to enter between

the teeth on the bar when the finger pieces 40 are actuated to depress the pawls and draw down the locking lever.

3. The combination with a movable carriage, of a locking and controlling lever mounted on the carriage so as to be capable 45 of swinging in a vertical plane, a stationary rack co-operating with the lever to lock the carriage in any one of a plurality of positions, a stationary toothed bar parallel with said rack, and mechanism mounted on the 50 carriage and co-operating with said toothed bar to depress the locking lever to release it from the rack, to cause the locking lever to be released when the carriage has moved a distance less than the spacing of the teeth 55 in the rack and in the bar, and to form a positive stop for the carriage when the movement of the carriage has continued far enough to permit the locking lever to drop freely between the teeth of its co-operating 60 rack.

4. The combination with a movable carriage, of a vertically swinging locking lever mounted on the carriage, a horizontal stationary toothed bar below said lever, a finger 65 piece movably mounted on the carriage beside said lever, a stop for limiting the movement of the finger piece in one direction, and a pawl carried by said finger piece and normally engaging with said lever so as to 70 carry said lever into a release position when the finger piece is actuated, said pawl having a part adapted to extend between two of the teeth on said bar before the finger piece is arrested by said stop.

In testimony whereof, I sign this specification.

JAMES E. PLEW.
